UNITED STATES PATENT OFFICE.

THOMAS CARROLL, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,163,738.

Specification of Letters Patent. Patented Dec. 14, 1915.

Application filed February 4, 1911. Serial No. 606,474.

To all whom it may concern:

Be it known that I, THOMAS CARROLL, a citizen of the United States, residing at Dayton, in the county of Montgomery and State of Ohio, have invented certain new and useful Improvements in Cash-Registers, of which I declare the following to be a full, clear, and exact description.

This invention relates to accounting machines and more particularly to machines of the type commonly known as "two-motion machines," that is, machines in which keys or manipulative devices are set and the operation completed by some other instrumentality, such as an operating handle or lever.

The principal object of this invention is to provide an improved form of actuators for the registering mechanism.

Another object of this invention is to provide an improved form of mechanism for actuating the indicators, so that they may move directly from one indicating position to another, without first returning to a normal starting position.

Another object of this invention is to provide an improved form of mechanism for recording the total, which is controlled by the resetting of the elements of the totalizer, this resetting of the totalizer elements positioning an inking device so as to record the total in a different color from the items, so that the totals may be readily distinguished from said items.

A further object of this invention is to provide an improved form of detent or latching device for holding the keys in their operated position.

A still further object of this invention is to provide an improved form of special indicator, which is so constructed that when brought into position to be displayed it conceals the amount indicators.

With these and incidental objects in view, the invention consists in certain novel features of construction and combinations of parts, the essential elements of which are set forth in appended claims, and a preferred form of embodiment of which is hereinafter described with reference to the drawings which accompany and form part of the specification.

Figure 1 is a central transverse sectional view through the improved machine. Fig.

2 is a view somewhat similar to Fig. 1 but taken just inside of the right-hand side frame of the machine. Fig. 3 is a view of the lock for the main operating shaft. Fig. 4 is an end elevation of the operating mechanism, also showing the total key. Fig. 5 is a rear elevation of the devices shown in Fig. 4. Fig. 6 is a detail view of one of the gears for operating the main driving shaft. Fig. 7 is an elevation of the total key and coöperating mechanism. Fig. 7^a is a partial top plan view of the totalizer elements and resetting devices therefor. Fig. 8 is a front elevation of the indicators and the gearing therefor. Fig. 9 is a side elevation of the totalizer. Fig. 10 is a transverse sectional view through the machine showing the "no sale" key and the special indicator controlled thereby. Fig. 11 is a partial front elevation of the printing mechanism and devices coöperating therewith. Fig. 12 is an end elevation of the record strip platen, and operating means therefor. Fig. 13 is a detail view of the alining devices for the printing mechanism. Fig. 14 is an end elevation of the mechanism for shifting the inking ribbon, so as to print the items and the total thereof in different colors.

Described in general terms the machine comprises a plurality of banks of manipulative devices, such as key levers, which, when operated, directly actuate totalizer elements and position type carriers for recording the items upon a record strip. Through suitable intervening mechanism the operation of the key levers also positions devices for determining the extent of movement of a set of indicators upon the operation of an oscillatory operating lever. The operation of this lever also actuates the platen mechanism to take an impression from the type carriers, after which, through suitable mechanism driven by the operating lever, the type carriers and mechanism for actuating the totalizer elements are returned to their normal positions.

When it is desired to record the total of the items entered upon the totalizer, a total key is depressed and the totalizer elements are reset to zero. The depression of the total key connects the actuators for the totalizer elements with said elements in such a manner, that, as the elements are returned

to zero, the actuators will be moved thereby in the same direction as they are moved when operated by the key levers. This movement of the actuators will set the type carriers in position to have printed therefrom the total as represented by the totalizer elements previous to their being returned to zero position. By the operation of the oscillatory hand lever the platen will be actuated to take an impression from the type carriers, and the indicators also will be set to display the total recorded upon the record strip. By the resetting of the totalizer elements to zero, the mechanism for inking the type carriers will be shifted so that the total will be printed in a different color from that of the items.

A suitable locking device is provided for the main operating lever, which is released upon the operation either of one of the amount keys or of the total key. A suitable interlocking mechanism is provided between the total key and the operating keys, so as to prevent operation of the total key and of one of the operating keys during the same operation of the machine.

When desired the platen operating mechanism may be disabled, so that the items and total thereof will not be recorded upon the record strip, but said items will, nevertheless, be entered on the totalizer elements.

A special indicator is also provided, which, when brought into indicating position, conceals the amount indicators.

Following this general description of the functions performed by the machine a more detailed description will now be given of the various parts for accomplishing these functions.

Manipulative devices 1 such as operating key levers are approximately centrally pivoted upon a transverse rod 2 which is supported by the side-frames 3 of the machine. These key levers are arranged in groups or banks of different denominations and near their rear ends have upwardly extending projections 4, graduated in height.

Coöperating with each bank of key levers 1 is a frame 5 which is loosely pivoted upon a rock shaft 6, the latter being suitably supported in the side-frames 3. The graduations 4 of each bank of key levers 1 are constructed to engage with a transverse plate 7 of the frame 5 coöperating with that particular bank. When any frame 5 is rocked by the operation of one of the key levers, its plate 7 will pass into a slot 8 formed in the operated key lever and lock the frame and the key lever together, thereby preventing an excess or overthrow movement of the frame 5. The plate 7 passes into the slot 8 because of the fact that the frame 5 and the key lever describe arcs of different circles which intersect each other.

The movement of all of the key levers 1

is limited by transverse shafts 9 and 10 which are suitably supported by the side-frames 3.

The extreme rear edges of all of the keys 1 are provided with two notches 11, in the upper ones of which normally rest forward projections 12 of frames 13, which are loosely mounted upon the shaft 9, there being one of these frames 13 for each group or bank of keys 1. The hubs of each of the frames 13 have extending inwardly therefrom pins 14 which enter a longitudinal groove 15 formed in the shaft 9. Upon the depression of any one of the operating keys 1, the upper notch 11 will rock the frame 13 coöperating therewith in an anti-clockwise direction, and through the pins 14 rock the shaft 9 in a similar direction. This shaft 9 has secured thereto an arm 16, see Fig. 3, which is provided with a laterally extending pin 17 that engages the rear edge of a locking pawl 18, which is pivotally mounted upon the shaft 9. This pawl 18 normally engages with a lug 19 projecting from a disk 20 which is secured to a shaft 21, which in turn is rotated by the main operating handle or lever 22, see Fig. 4, as hereinafter more fully described. From this it will be seen that upon the rocking of the shaft 9 by the depression of any one of the key levers 1, the locking pawl 18 will be withdrawn from engagement with the lug 19 and thereby will release the shaft 21 and the operating lever 22. The locking pawl 18 at its pivotal point is provided with an elongated slot 23 which permits an upward movement of the pawl 18 by a spring 24 when said pawl is rocked from under the lug 19. The tendency of spring 24 is to rock the pawl 18 in a clockwise direction as well as to lift it upwardly, so that as the lug 19 is carried away from the upper end of the pawl upon the beginning of rotation of shaft 21, the upper end of said pawl will be moved in the path of the lug 19 and as the disk 20 nears the end of its movement the lug 19 will engage with the upper end of the pawl and restore it to locking position as shown in Fig. 3.

Fastened to the plate 7 of each frame 5 is a rearwardly extending arm 25, which at its rear end is provided with a pin 26 that plays in a slot 27 formed in a movable rack 28, which is guided in its movement by the shafts 9 and 10. These racks mesh with pinions 29 mounted upon the ends of nested sleeves 30 that surround a transverse shaft 31 suitably mounted in the side-frames 3. These sleeves at their other ends carry segments 32, see Fig. 13, which mesh with pinions 33 secured to the ends of a second set of nested sleeves 34, see Fig. 11, which sleeves at their other ends carry type carriers 35 for recording items and the total thereof as hereinafter more fully described.

The racks 28 are provided at their upper ends with studs 36, see Figs. 1, 2 and 7, which studs project through elongated slots 37 formed in plates 38. These plates at their 5 upper ends are forked, and the prongs of the forks are formed into rack portions 39 and 40. The rack 39 of each plate 38 normally engages with a pinion 41 which is attached to a larger pinion 42 which in turn 10 meshes with a pinion 43 carried by one of the totalizer elements 44. The rack portions 40 are provided with an elongated slot 45 through which extends a rod 46 that acts as a guide for the movement of the upper 15 ends of the racks 38. The lower portion of each rack 38 is forked and straddles the shaft 9 which shaft acts as a guide for the lower portion of said rack plates 38. From this it will be seen that the differential 20 movement of the frames 5 imparted thereto by the operating key levers 1, will, through the racks 28 and the actuating plates 38, impart a similar movement to the totalizer elements 44.

25 A plurality of pawls 47, one for each rack plate 28, are loosely mounted upon a transverse rod 471, which is suitably mounted in the side frames 3. Each of these pawls 47 is forked at its upper end, the rear prong 30 of which contacts with the rear side of one of the frames 13, while the forward prong is arranged to engage with ratchet teeth 48 formed on the rear edge of the companion rack plate 28. These pawls 47 are held in 35 contact with the frames 13 by leaf springs 49, which are secured to the pawls 47 and have their free ends contacting with a transverse shaft 50, the latter being suitably mounted in the side frames 3. From this 40 description it will be seen, that, upon the beginning of operation of any one of the keys, the companion frame 13 will be rocked counter-clockwise and thereby rocks the pawl 47 co-operating therewith in a clockwise direction, which movement will withdraw the forward prong of said pawl from 45 engagement with the ratchet teeth 48 of the rack plate 28, in which position said pawl will be held while the plate 28 is being adjusted by the operating key. At the end of 50 the down stroke of the operated key the projection 12 of the operated frame 13 will pass into the lower notch 11 of said key, by this movement permitting the forward 55 prong of the pawl 47 to spring into engagement with the ratchet teeth 48 of the rack plate 28, thereby latching the plate 28 and key 1 connected thereto in their operated 60 positions. By the operation of the operating lever 22 the pawl 47 will be withdrawn, and the key 1 and plate 28 will be positively restored to normal positions, as will appear from the description hereinafter given. The indicators, which are of the type that 65 are driven directly from one position to

another without returning to a normal starting position, are provided with an improved form of mechanism for accomplishing this function, which now will be described.

The upper ends of the racks 28 are connected to the forward ends of plates 51 by the studs 36, the rearward ends of said plates 51 being provided with antifriction rollers 52 which play in elongated slots 53 formed in indicator actuating racks 55. These 70 racks at their upper ends mesh with pinions 56 secured to indicators 57 for displaying the amount represented by the keys depressed. Approximately at their centers the plates 51 are provided with triangular 75 slots in which a rod 58 plays. This rod 58 is supported by arms 59 which are fast to the rock shaft 50. This rock shaft 50 has secured thereto an arm 60, which is provided with a laterally extending pin 61 that 80 plays in a recess 62 formed in the lower end of an arm 63, which is centrally pivoted as at 64 upon one of the side frames 3. The upper end of this arm 63 is provided with a roller 64, which plays in a cam groove 65 85 formed in a disk 66 secured to the driving shaft 21. The shape of the cam groove 65 is such that upon each rotation of the shaft 21 the frame composed of the rod 58 and the side-arms 59 will be oscillated an invariable extent first in an anti-clockwise direction and then back to normal position. From the above description it will be seen 90 that, after the forward ends of plates 51 have been positioned by the differential 95 movement of the racks 28 the pawls 47 will latch said racks in their adjusted position, so that upon the rotation of the shaft 21 the cross rod 58 playing in the triangular 100 slots of the plates 51 will, in its forward movement, contact with either the upper or lower walls of the triangular slots, and thereby position the rear ends of said plates, which, through the racks 55, will rotate the 105 indicators 57.

110 The racks 55 have formed on the rear edges thereof V shaped notches 67 with which the end of a locking and alining plate 68 engages, to hold the indicators in their adjusted positions. This plate 68 is 115 secured at its lower end to a rock shaft 69 which is supported by the side frame 3. This rock shaft has extending forwardly therefrom an arm 70 to which is connected the lower end of a pitman 71, the upper end 120 of which is forked and straddles the rotation shaft 21. Near its upper end the pitman 71 is provided with an anti-friction roller 72 which plays in a cam groove 73 formed in a disk similar to the disk 66 and which is secured to the shaft 21. Upon the beginning of the rotation of the shaft 21 the cam groove 73 will rock the plate 68 out of the notches 67 of the racks 55, so that said 125 racks may be adjusted in order properly to 130

position the indicators, after which the cam groove 73 will rock the plate 68 into the notches 67 to lock and aline the indicators. With this style of indicators, which is moved directly from one position to another without returning to zero or normal position, there is a tendency, when the indicators are released, for the actuating racks to return said indicators to normal position, due to the weight of said racks. When successive sales of the same amounts are made this returning of the indicators toward normal position would necessitate the resetting of the indicators for each sale, and in order to prevent this unnecessary operation of the indicators, the actuating racks for the different sets of indicators, for displaying the transactions to the front and back of the machine, are connected in such a manner that when one set of actuators are operated the other set of actuators will be moved in the opposite direction. From this general statement it will be seen that the different sets of actuators, being connected and of equal weight, and moving in opposite directions, will offset the tendency of either set of actuators to return the indicators connected thereto to zero or normal position. One form of mechanism for accomplishing this object is as follows.

Referring now to Fig. 8, it will be seen that the indicators shown therein are constructed to indicate transactions in which English currency is used, but it is to be understood that the invention is equally applicable to machines in which other monetary systems are employed. The rack 55 which actuates the farthing indicator of the front set of indicators, meshes with a pinion 75 secured to a transverse shaft 76. Near its other end this shaft carries a pinion 77 which is similar to the pinion 75 and which meshes with a broad pinion 78 loosely mounted on a transverse shaft 79. This pinion 78 meshes with a rack 80 which in turn engages with a pinion 81 secured to the farthings indicator of the back set of indicators. From this it will be seen that, through the intermediate pinion 78 the rack 80 for the back indicator will be driven in the opposite direction, from that in which the rack 55 is driven, and consequently the movements of the racks 55 and 80 in opposite directions will offset any tendency to rotate either indicator to zero or normal position. The rack 55 for the pence indicator meshes with a pinion 82 secured to one end of a sleeve 83, loose on shaft 76, and the other end of which has secured thereto a pinion 84 which meshes with a broad pinion 85, loose on shaft 79 and which, through one of the back set of racks 80 and pinions 81, rotates the pence indicator of the back set. The rack 55 for the units of shilling wheel meshes with a pinion 86 secured to the shaft

79, to which also is secured a pinion 87 that meshes with a broad pinion 88 loosely mounted upon the shaft 76, this broad pinion 88 in turn driving the rack 80 for the units of shilling indicator for the back set. The indicator for displaying tens of shillings toward the back of the machine is operated through the ten shilling rack 55, pinions 89, 90 and 91 and the rack 80 and pinion 81. The pounds wheel is an enlarged single wheel and carries two sets of numerals thereon which are arranged in reverse order. The rack 55 for driving this indicator also meshes with a pinion 92 loosely mounted upon the shaft 79 and 80 against which abuts a coiled spring 93, so as to offer resistance to the turning of this enlarged indicator, and thereby preventing movement of said indicator by gravity.

A "no sale" key 137, see Fig. 10, is mounted upon the transverse rod 2 adjacent to the amount keys 1 and near its rear end has connected thereto the lower portion of a link 138, the upper portion of which is provided with an elongated slot 139 through which a pin 140 extending from an arm 141 passes. This arm 141 is, at its rear end, loosely mounted upon a transverse rod 142 which supports the previously described amount indicators 57, the forward end of the arm 141 being provided with a pawl 143 which is centrally pivoted thereon. This pawl 143 is provided at both ends with hook portions, and is normally held in the position shown in Fig. 10, with its lower end abutting a pin 144 carried by the link 138, by a spring 145, the ends of which are connected with the pawl 143 and the arm 141.

Upon each operation of the machine a concealing means composed of shields 146 carried by arms 147, which are centrally pivoted upon the rod 142, is moved to a position to conceal the indicators 57 during their adjustment, and then returned to normal position at the end of the operation of the machine so as to expose the adjusted indicators. This movement of the concealing means is accomplished by a disk 148 secured to the shaft 21 and which is provided with a cam groove 149 in which a roller 150 projecting from the forward end of a pitman 151 extends. The rearward end of the pitman 151 is connected to the vertical arm of a bell crank lever 152 which is loosely mounted upon a guide rod 153. One of the arms 147 of the flash or concealing means is connected to the horizontal arm of the bell crank 152 by a link 154. From this it will be seen that upon each operation of the shaft 21, the shields 146 of the concealing means will be moved to a position to conceal the indicators 57 and near the end of the rotation of the shaft 21 will be returned to normal position.

When the "no sale" key 137 is depressed the link 138 will be elevated carrying the pin

144 projecting therefrom away from the lower portion of the spring drawn pawl 143 so that the upper portion will contact with the rear edge of the front shield 146. Upon 5 the rotation of the shaft 21 by the operating lever 22, the concealing means will be moved and the shield 146 will pass under the upper hook portion of the pawl 143, so that when the concealing means is returned to normal 10 position at the end of the operation of the machine, the forward shield 146 will elevate the pawl 143 and the arm 141 to which said pawl is pivoted. This elevation of the pawl 143, will, through the lower hook portion, 15 position additional concealing means or flashes 155 so as to conceal the front and back sets of indicators. These flashes 155, while used to conceal the amount indicators 57, are also used as "no sale" indicators. In 20 the adjustment of the "no sale" indicators or flashes 155 to indicating position, the forward one of the said flashes will contact with the under side of the shield 146 of the main concealing means while the lower portion of 25 the rear "no sale" indicator 155 will contact with the upper part of the rear shield 146 so that upon the succeeding operation of the machine the "no sale" indicators or flashes 155 will be returned to their normal 30 position by the shields 146 of the main concealing means, in which position the "no sale" indicator will remain until the "no sale" key 137 is again depressed. In the return of the "no sale" indicators to their normal 35 non-indicating position the lower end of the pawl 143 will contact with the stud 144 and thereby rock the upper hook portion of said pawl out of engagement with the front flash 146 so that the said flash or shield may 40 be returned to its normal non-concealing position independently of said pawl. A stud 156 projects from the arm 141 and normally contacts with the forward edge of the link 138 so as to limit the downward movement of 45 the arm 141. The "no sale" key has co-operating therewith one of the latching frames 13 similarly to the amount keys, which latching frame is provided with a stud 14 which projects into the longitudinal 50 groove 15 of the shaft 9, so that by the operation of the "no sale" key the shaft 9 will be rocked to release the main operating mechanism of the machine in the same manner as if one of the amount keys were operated. 55 It might be here mentioned that the width of the longitudinal slot 15 formed in the shaft 9 is greater than the thickness of the studs 14 which project from the frame 13, thus permitting any one of the frames 13 to 60 rock the shaft 9 independently of any of the other frames. This shaft is returned to its normal position by a spring 157, the ends of which are connected to the said shaft and to one of the side frames 3. 65 The main operating lever 22, see Figs 4

and 5, which is employed to drive the main driving shaft 21, has secured to the hub thereof a segmental rack plate 94, which meshes with a gear 95 loosely mounted upon the shaft 21 and also with a pinion 96 mounted upon a stud 97 projecting from one of the side frames 3. This pinion 96 and a similar pinion 98 are fast on a sleeve 99 and the pinion 98 in turn meshes with a gear 100 which is mounted loosely upon the shaft 21 70 adjacent to the gear 95. The gears 95 and 100 are provided with spring pressed pawls 101 and 102 respectively which are arranged to engage with a longitudinal groove 103 formed in the shaft 21 and drive said shaft 80 as the gears are rotated.

As the operating lever 22 is moved forward in an anti-clockwise direction the segment 94 will, through the pinions 96 and 98, rotate the gear 100 in a similar direction 85 and through the pawl 102 carried by said gear 100 rotate the shaft also in an anti-clockwise direction. The segment 94 meshing with the gear 95 directly will drive said gear in clockwise direction so that the pawl 90 101 will have no effect upon the shaft 21 during the forward movement of the operating lever 22. This forward movement of the operating lever 22 will rotate the shaft 21 and the gear 95 a half rotation in 95 opposite directions, so that the pawl 101 will engage with the longitudinal slot 103 at the end of the forward movement of the operating lever 22. Upon the return movement of the lever 22 the pawl 101 will now 100 pick up the shaft 21 and complete the rotation thereof while the gear 100 carrying the pawl 102 will rotate idly back to normal position. It will be seen that by this construction the oscillatory movement of 105 the operating lever 22 is converted into a rotary movement of the shaft 21.

A printing mechanism forms a part of this invention, and said mechanism is constructed to record upon a record strip items 110 entered in the machine and the total thereof, the items and the total being recorded in different colors, so that they may be readily distinguished from each other. A description of the preferable form of mechanism for accomplishing these functions 115 now will be given.

The shaft 21, at the opposite end from that upon which the gears 95 and 100 are mounted, has attached thereto a disk 104 120 (Fig. 12), which is provided with a cam groove 105 in which plays an anti-friction roller 106 projecting from one end of a pitman 107, the other end of said pitman being connected to a link 108 which is pivotally mounted upon a stud 109 projecting from one of the frames 3' of the printing mechanism. The pitman 107 has extending therefrom a stud 110 which plays in a recess 111 formed in one end of an arm 112 that 125

130

is loosely mounted upon a stud 113 projecting from the printer frame. This arm 112 is connected through a hub 114 to a forwardly extending arm 115 which carries a plate 116 that in turn carries the record strip 117 and a platen 118. The arm 115 is provided with notches or recesses 119 and 120 into which project studs 121 and 122 extending from the plate 116 and by this means the said plate 116 is supported upon the arm 115. An adjusting screw 123 extends through the plate 116 into contact with the forward end of the arm 115 so as to adjust the surface of the impression platen 118 relative to the type carriers 35.

The record strip 117 is fed from a supply roll 124, mounted upon the plate 116, over the platen 118 and thence to a storage roll 125 also mounted upon the plate 116. From this it will be seen that upon the rotation of the shaft 21 in the direction of the arrow the pitman 107 will be reciprocated, and, through the stud or roller 110, rock the arms 112 and 115 so as to carry the platen 118 into contact with the type carriers 35 to take an impression upon the record strip 117. The storage roll 125 for the record strip is provided with a ratchet wheel 126 with which a feed pawl 127, pivotally mounted on one of the printer frames 3' of the machine engages, and is held in engagement with said ratchet 126 by a spring 128. When the platen 118 is elevated to take an impression from the type wheels 35, as previously described, the ratchet 126 will also move upwardly, which movement will carry the next rearward tooth of the ratchet into engagement with the forward end of the feed pawl 127, so that as the frame 116 carrying the platen 118 and the ratchet 126 is returned to normal position, the said ratchet and storage roll 125 will be advanced one tooth. A retaining pawl 129, carried by the plate 116, engages and holds said ratchet 126 and prevents retrograde movement thereof. A forward extension 130 of the arm 112 contacts with a stud 131 projecting from the printer frame, and thereby limits the clockwise movement of the arms 112 and 115.

The plate 116 carrying the platen 118 and the supply and the storage rolls 124 and 125 may be detached from the arm 115 by raising the rear end of said plate, so that the stud 121 will pass out of the notch or recess 119, during which movement the stud 122 acts as a pivotal point for the plate 116. After the pin 121 has passed out of the notch 119, all that is necessary to remove the plate 116 is to move said plate forwardly, until the stud or roller 122 passes out of the notch or recess 120 formed in the rear end of arm 115.

The link 108 is adjustable relative to the stud 109 so that the platen operating mech-

anism may be disabled, and this link is provided with a plate carrying suitable characters for indicating whether the platen mechanism is disabled or enabled. An enlarged slot 132 is formed in the lower end of the link 108 and is provided with offsets 133, the upper of which engages with the stud 109 when the platen operating mechanism is enabled and the lower of which is arranged to engage with the stud 109 when the said platen is disabled. The link 108 is provided with a disk 134 which is mounted on the inside of the frame 3' and also with a knob 135 which projects through an opening 136 formed in the said frame. This disk 134 is provided with the characters "On" and "Off", which are arranged to be displayed singly through the opening 136 to indicate the condition of the platen mechanism, and as shown in Fig. 12, the platen operating mechanism is in operative condition. When it is desired to disable the platen mechanism, the operator grasps the knob 135 and moves the lower end of the link 108 forward slightly, and then elevates said link until the lower offset 133 of the slot 132 engages with the stud 109 projecting from the frame 3. This elevation of the link 108 carries the roller 110 out of the recess 111, so that when the pitman 107 is reciprocated it will not operate the arm 112 of the platen mechanism, and consequently no impression will be taken from the type carrier 35. When the link 108 is in this position the character "Off" will appear through the opening 136 in the frame 3'.

To align the type carriers the shaft 21 carries a camming disk 158, see Fig. 13, which, upon the beginning of the rotation of the said shaft, will engage with a roller 159 carried by the upper end of an arm 160 which is centrally pivoted upon one of the side frames of the machine. At its lower end this arm is provided with a plate 161, which, when said arm is rocked by the cam 158, passes into engagement with the teeth of the pinions 33 and thereby alines the type carriers 35, so that a perfect impression may be taken from said type carriers.

An ink ribbon forming a part of the printing mechanism now will be described. This ribbon is employed to ink the type carriers and is fed, by operations of the machine, from one spool to another, and the feed automatically reversed when said ribbon is nearly unwound from either of said spools. A frame 162 composed of right angle plates 163 and 164, see Figs. 11 and 14, is secured to the left-hand side frame 3 by studs 165 which project through elongated slots 166 formed in the plate 163 of said frame. Sleeves 167 are mounted upon suitable studs projecting from the plate 164 and said sleeves carry spools 168 attached to which are the ends of an inking ribbon 169. This

ribbon is led from one of the spools beneath the type carriers 35, see Fig. 11, then around a stud 170 extending from an arm 171 forming a part of the frame 162 and thence back to the other spool. Slidably mounted upon the sleeves 167 is a plate 172 which is connected by a pin 173 to the lower end of a plate 174 which is suitably guided upon a supporting frame 175 for the type carriers. 5 This plate 174 at its upper end is bent at right angles and straddles the driving shaft 21. Projecting from the upper end of the plate 174 is a pin 1755 which plays in a cam groove 176 formed in a disk 177 secured to the shaft 21. The shape of the groove 176 is such that it reciprocates the plate 174, and through the pin 173, the plate 172. Centrally pivoted upon the plate 172 is a pawl 178, see Fig. 11, the ends of which are 10 arranged alternately to engage with ratchet wheels 179 secured to the sleeves 167. This pawl 178 is held frictionally in position to engage either of the ratchets 179 by a retaining pawl 180, which is pivotally mounted upon the plate 172 and is held into engagement with either side of a V shaped projection of pawl 178 by a spring 181. At its center the pawl 178 has projecting rearwardly therefrom a pin 182, which is in the 15 path of a pin 183 projecting from a worm gear 184, the latter meshing with a worm 185 secured to the upper sleeve 167, carrying the upper ribbon spool 168 and the upper ratchet 179. It will be seen from this description that the worm gear 184 is slightly moved upon each operation of the machine, and that after a certain number of operations the pin 183, carried by said worm gear, will contact with either the upper or lower 20 side of the pin 182 projecting from the feed pawl 178, so as to rock said pawl about its pivotal point, whereby the disengaged portion of the pawl will engage with its ratchet 179, and upon succeeding operations of the machine feed the ribbon in a reverse direction, this pawl 178 being frictionally held in its adjusted position by the retaining pawl 180. A double pointed retaining pawl 186 slidably mounted upon the plate 164 is 25 held in engagement with the ratchets 179 by a spring 187 so as to prevent accidental displacement of the ribbon spools.

After an impression has been taken from the type carriers by the platen, a pin 188, 30 see Fig. 2, projecting from a disk 189, secured to the shaft 21, will contact with the forward prong of a V shaped plate 190 which is rigidly secured to the shaft 9 and rock said shaft in an anti-clockwise direction, 35 which movement will, through one of the side walls of the longitudinal slot formed in said shaft contacting with the studs 14, rock the latch frames 13, and thereby withdraw the projections 12 of said frames from the 40 notches 11 of the keys 1. This rocking of

the frames 13 will rock the pawls 47 also, against the tension of the leaf spring 49, and thereby withdraw the ends of said pawls out of engagement with the ratchet teeth 48 formed in the rear edge of the rack 70 plates 28.

Immediately after the withdrawal of the pawls 47 from engagement with the ratchet teeth 48 of the plates 28 the shaft 6 will be rocked in a clockwise direction by a cam 75 191, see Fig. 2, secured to the shaft 21, which disk will move forwardly a pitman 192 the forward end of said pitman being secured to an arm 193 which is fast to the rock shaft 6. This rocking of the shaft 6, will, through pins 194, see Fig. 1, carried by said shaft and engaging with the walls of recesses 195 formed in the hubs of the frames 5, which are pivoted upon said shaft, positively restore the previously adjusted frames to normal position, and, through the pins 26 playing in the slots 27 of the racks 28, restore 80 said racks to normal position.

Previous to the restoration of the differentially movable frames 5 and the racks 28 90 to normal positions, the actuating plates 38 mounted upon the racks 28 will be shifted to an intermediate position so that the pinions 41 will be between the rack portions 39 and 40 of the actuating plates 38, whereby 95 the return movements of the actuating plates 38 with the differentially movable frames 5 and the rack plates 28, will have no effect upon the totalizer elements 44. This shifting of the actuating plates 38 to intermediate positions is accomplished by a cam disk 196, see Fig. 7, secured to the driving shaft 21, which disk shortly after the beginning of the rotation of said shaft, will draw rearwardly a pitman 197 having its extreme forward end connected to the lower end of an arm 198, the upper end of which is secured to a total key 199. One end of the rod 46, which acts as a guide for the actuating plates 38, projects into a recess 200 formed in the 100 arm 198, so that when the lower end of the said arm 198 is moved rearwardly as just described, the rod 46 will also be moved rearwardly. This rod is supported by vertical arms 201, which are fast at their 110 lower ends to a shaft 202, suitably mounted in the side frames of the machine. Near the end of the rotation of the shaft 21, the pitman 197 will be moved forwardly and thereby shift the actuating plates back to 120 their normal positions, that is, with the rack portions 39 of said plates in engagement with the pinions 41. In the rocking or shifting of actuating plates 38 the shaft 9 acts as a pivot for said plates, and this rocking 125 movement is independent of the rack plates 28 owing to the elongated slots 37 which are formed in said plates, and through which the studs 36 pass.

It will be recalled that the shaft 9 is rocked 130

upon the operation of either the amount keys 1 or the "no sale" key 137, and a hook portion 262, see Fig. 2, of the V shaped plate 190 secured to said shaft 9 will in either case 5 pass into the path of a shoulder 263 formed upon the disk 189, and thereby prevent the rotation of the shaft 21 until the key is fully depressed, when the forward projection 12 of the latching frame 13 will enter the lower 10 notch 11 of the operated key. This will permit the shaft 9 to return to its normal position by its spring 157, see Fig. 10, thereby unlocking the shaft 21, so that the same may be rotated by the operation of the lever 22. 15 One portion of the disk 189 is reduced in radius so that when the pin 188, projecting from said disk, contacts with the forward arm of the V shaped plate 190 during the rotation of the shaft, the hook portion 262 of said plate will not bind against the periphery of the disk 189.

In order to prevent the operation of any unoperated keys 1 during the actuation of the lever 22 the shaft 50, see Fig. 1, which is 20 oscillated at each operation of the lever 22, is provided with projections 203, which, upon the beginning of the forward movement of the operating lever 22, will contact with the rear edges of the latching pawls 47, 25 and hold said pawls from rearward movement until the projections 203 rock away from the pawls 47 by the return stroke of the operating lever 22.

Mechanism is provided for recording the 30 total, and this mechanism is controlled by the totalizer elements, so that in order to record the total it is necessary to reset the totalizer elements to zero, and this resetting of the totalizer elements will advance the 35 type carriers through the distance the said totalizer elements are reset. When it is desired to record a total, the total key 199, see Figs. 4 and 7, which is mounted upon shaft 204, which supports the pinions 41 and 42, 40 and upon a stud 205, is pushed rearwardly, which rearward movement will also carry the upper end of the arm 198 rearwardly, and, through the guide shaft 46 projecting into said arm, will carry the forward rack 45 portions 40 of the actuating plates 38 into engagement with the pinions 41. Now, when the totalizer elements 44 are rotated in the 50 reverse direction from that in which they are driven by the rack plates 39, they will, through the pinions 43, 42 and 41, elevate the actuating plates 38 in the same manner as when said plates are operated by the amount keys 1. This movement of the actuating plates will, through the racks 28 to 55 which said plates are connected, rotate the type carriers 35 through the pinions and nested sleeves connected to said racks, as previously described.

It is to be understood that there are other 60 racks 28 and actuating plates 38 than those

directly operated by the amount keys 1, which additional racks and actuating plates are for the purpose of setting type carriers 35 under the control of the higher denominational elements 44 of the totalizer, which 65 are not operated directly upon the operation of the amount keys, but receive their movement through the transfer devices shown in Fig. 9 and hereafter described. After the recording of the total, which takes place 70 upon the operation of the operating lever 22, in a manner similar to the recording of the items, these additional actuating plates 38 and racks 28 are restored to their normal positions by fingers 265, see Fig. 2, which 75 contact with pins 266 projecting from the additional actuating plates 38. These fingers 265 project rearwardly from a sleeve 267 that is loosely mounted upon the shaft 202, and extending upwardly from this 80 sleeve is an arm 268, to which is connected the rear end of a link 269, the forward end of said link being connected to an arm 270 secured to the rock shaft 6. From this it 85 will be seen that the additional racks 28 and the plates 38, which are used only in the recording of totals and with which no differentially movable plates 5 co-operate, are positively returned to their normal positions 90 through devices slightly different from those which return such of the racks 28 and actuating plates 38 as are directly operated by the amount keys 1, but the return of all 95 said plates occurs through the same instrumentality, namely, the rock shaft 6. This 100 inward movement of the total key 199 will rock the shaft 202 bearing the arms 201 which support the guide rod 46 so that an arm 206, see Fig. 3, extending from said 105 shaft 202 will, through a pin 207 extending from the arm 206, rock the latch pawl 18 from engagement with the stud 19 by contacting with a forward projection of said 110 latch pawl, and thereby release the driving 115 shaft 21 and the operating lever 22 for actuating said shaft. By the operation of the 120 lever 22, the shaft 21 will be rotated and a cam portion 196', formed in the disk 196 carried by the shaft 21, will engage with a roller 208 projecting from the total key and 125 return said key to its outer position, which movement will ordinarily return the actuating plates 38 to their normal position, as shown in the figures of the drawings, but simultaneously with the outward movement of the total key 199 the pitman 197 will be drawn rearwardly, which movement will counter-act a portion of the outward movement of the actuating plates 38 so that said 130 plates will be held in an intermediate position to permit the return of said actuating plates by the return movement of the differentially movable frames 5, as heretofore described.

The totalizer elements 44 are loosely

mounted upon a shaft 209, the outer right hand end of which is provided with a knurled knob 210, see Figs. 4, 5 and 7^a. Just inside of the right hand frame 3 of the machine a disk 211 is also secured to the shaft 209, and this disk is provided with a notch 212 in which rests a pin 213, projecting from the total key, when said key is in its outermost position, and thereby locks the said shaft from rotation. From this it will be seen that it is impossible to reset the totalizer elements without connecting the actuators 38 to said elements and through said actuators adjusting the type carriers into position for printing the total. This total key 199 is latched in its operated position by a pawl 214 which is secured to a shaft 215. This shaft has extending rearwardly therefrom, see Fig. 7, an arm 216, having a pin 217 which projects into a cam groove 218 of a disk which is secured to the driving shaft 21. Upon the first movement of the shaft 21 the cam groove 218 will rock the shaft 215, so as to release the pawl 214 from engagement with the projection of the total key, whereupon said total key may be returned to its outermost position.

As previously mentioned, the totalizer wheels are rotated in an opposite direction when they are being reset to zero from that in which they are rotated when being actuated by the rack plates 38, and in order to reset these totalizer wheels or elements 44 to zero positions they are provided with projections 219, see Fig. 7^a, with which projections 220 extending from collars 221 are arranged to engage and rotate said wheels in a reverse direction. The projections 220 of the collars 221 are normally out of the planes of movement of the projections 219 of the totalizer elements 44, so that the said totalizer elements may be repeatedly rotated without contacting with the projections 220 of the collars 221. Upon the rotation of the shaft 209 supporting the totalizer elements 44, the projections 220 will be moved into the planes of movement of the projections 219 by a pin 222 fast to and projecting from shaft 209 and which normally stands in a camming recess 223 of a boss 224 on the right hand side frame 3. The continued rotation of the shaft 209 by the knurled knob 210, will bring the projections 220 into contact with the projections 219, and carry said wheels back to normal or zero position. Near the end of rotation of the shaft 209, a pin 209' projecting from the shaft will engage with a camming portion of a plate 210', Fig. 7^a, secured to the left hand side frame 3 and positively restore the shaft 209 to its normal position. The shaft will be arrested at the end of its rotation by a pin 225, see Figs. 4 and 7, extending laterally from the disk 211 secured to the shaft, which will engage with a hook portion formed at the forward

end of a pawl 226 which is pivoted upon a transverse shaft 227. The pawl 226 is released from engagement with the pin 225, upon the beginning of rotation of the shaft 21, by a pin 228 projecting from an arm 229 secured to the rock shaft 215. Upon the beginning of rotation of the said shaft 21 the cam groove 218, see Fig. 7, will rock the shaft 215, and through the pin 228 engaging with the underside of the pawl 226, elevate the forward end of said pawl, which pawl will immediately be drawn rearwardly by a spring 230, the ends of which are secured to the pawl and to the side frame. This longitudinal movement of the pawl 226 is permitted by an elongated slot 231 through which the shaft 227 passes. As previously mentioned the items and the total are printed in different colors so that they may be readily distinguished from each other, and the bicolor ink ribbon used for this purpose is shifted in the following manner. Upon the rotation of the shaft 209, as just described, a cam disk 247 fast thereon, see Fig. 14, will engage with a roller 248 projecting from the center prong 249 of a lever 250, which is pivotally mounted as at 251 upon the left hand side frame of the machine, and rock said lever in a clockwise direction. This movement of the lever will carry a hooked end of a prong 252 of said lever, into position to intercept the movement of a pin 253 carried by the cam disk 247, and thereby aid the pin 225 and pawl 226 in arresting the shaft at its normal or zero position. This clockwise movement of the lever 250 will carry a roller 254, projecting from another prong of said lever, into the path of a camming projection 255 of the disk 177, which projection, at the end of the rotation of the shaft 21, will engage with the roller 254 and restore the lever 250 to its normal position as shown in Fig. 14. This lever 250 is further provided with a downwardly extending arm 256, which at its extreme lower end is forked and straddles a pin 257, projecting from the plate 163 of the frame 162 carrying the inking ribbon 169. It will be seen that as lever 250 is rocked in a clockwise direction, as just described, the forked end of the arm 256 of said lever will carry the frame 162 rearwardly upon the studs 165, which support said frame upon the side frame of the machine. The plate 163 for the frame 162 has projecting therefrom a roller 258, which is arranged to pass into V-shaped notches 259 formed on the underside of a pawl 260, which is pivoted to one of the studs 165 which support the frame 162. This pawl is drawn into contact with the roller 258 by a spring 261, the ends of which are attached to the free ends of the pawls 260 and to the forward stud 165. This pawl 260 and the stud 258 are arranged to hold the frame 162 carrying the inking ribbon 169 in its ad-

justed position and to prevent accidental displacement thereof. The inking ribbon 169, as shown in Fig. 14, has fields of different colors through one field of which the items 5 are arranged to be printed, while through the other field the total is printed, thereby distinguishing the total from the items. It will be noted that the frame 162 carrying the ribbon 169 is not returned to its normal position 10 by the projection 255 engaging the roller 254 until the very end of the operation of the machine, while the impression is taken from the type carriers at the end of the first half rotation of the main operating shaft 21, as 15 fully shown in Fig. 12.

In order to prevent manipulation of the totalizer elements 44 it is desirable at all times to have said elements under the control of either the actuators 38 or the transfer devices. Normally the actuators 38 are 20 in engagement with the totalizer elements while the transfer devices are disengaged therefrom. In ordinary operations of the machine where items are accumulated upon 25 the totalizer the transfer devices are engaged with the totalizer elements previous to the disengagement of the actuators 38 by the following mechanism.

Referring now to Fig. 7 it will be seen 30 that the cam groove 218, in which rests the roller 217 of the arm 216, is so shaped that upon the beginning of rotation of shaft 21 in the direction of the arrow shown in said figure the arm 216 will be rocked in an anti-clockwise direction and also the shaft 215 to 35 which the arm 216 is secured. This shaft is provided with upwardly extending arms 275, Fig. 9, one for each transfer device or element 264, and each arm at its upper end 40 is provided with a pin 276 that extends into an elongated slot 277 of its companion transfer device 264. From this it will be seen that upon the rocking of the shaft 215 the transfer devices 264, which are slidably 45 mounted upon the shaft 227, will be moved into engagement with the pinions 43 of the totalizer elements 44. The purpose of the elongated slots 277 in the transfer devices 264 is to permit movement of said devices in 50 effecting the transfer independent of the arms 275. The cam groove 218 will hold the transfer devices 264 in engagement with the totalizer elements until near the end of the operation of the machine.

55 After the engagement of the transfer devices with the totalizer elements by the cam groove 218, the actuators 38 will be moved to an intermediate position by the cam disk 196, in which position the actuators are disengaged from the totalizer elements. While 60 in this intermediate position the actuators will be returned to their normal positions as previously described, and then reengaged with the totalizer elements previous to the 65 disengagement of the transfer devices from

said totalizer elements. This intermediate position of the actuators occurs also upon the operation of the total key preparatory to the recording of the total. It will be recalled that upon the operation of the total 70 key 199 the actuators 38 will be rocked or shifted so as to bring the forward rack portions 40 of said actuators into engagement with pinions 41 and disengage the portions 39 therefrom. During this shifting 75 of the actuators there occurs a time when neither rack portion of the actuators is in engagement with the pinions 41, this intermediate position being necessary to permit the restoration of the actuators independently of the totalizer elements. By holding the total key with the actuators in their intermediate position it would be possible to manipulate the totalizer elements if access were gained thereto but this is overcome by 80 engaging the transfer devices with said elements during this period, which is accomplished in the following manner. Upon the operation of the total key 199 the latch pawl 214 will be rocked, Fig. 7, and unless the 85 total key is completely operated the pawl 214 will remain rocked. This pawl as previously explained is fast to the shaft 215 and consequently the said shaft will be 90 rocked. The roller 217 carried by the arm 95 216, which is secured to the shaft 215, normally rests in an enlarged portion of the cam groove 218, which permits movement of the arm 216 with the shaft 215. This rocking of the shaft 215 will, through the arms 100 275 and pins 276, Fig. 9, carried thereby move the transfer devices 264 into engagement with the totalizer elements. After the total key is fully depressed, by which time the portions 40 of the actuators will be in 105 engagement with the pinions 41, the shaft 215 will be returned to normal position by a spring 278, which is coiled about the shaft and has one end secured thereto while the other end is coiled about the shaft 204. This 110 return of the shaft will withdraw the transfer devices 264 from engagement with the totalizer elements.

The transfer devices above described are substantially identical with those shown and 115 described in a copending application of the present inventor which was filed Feb. 5, 1907, and numbered 355,924. This particular transfer mechanism forms no part of the present invention except in combination 120 with the elements of this invention and it is thought no definite description need be given thereof.

Means will now be described for preventing the operation of both one of the key levers 1 or 137 and the total key 199 during a single operation of the machine. This is essential as otherwise the machine would be open to manipulation. When an amount key or the "No Sale" key 137 is operated the 130

shaft 6 will be rocked in a counter-clockwise direction by the frames 5 and this shaft at its right hand end is provided with a plate 232, see Fig. 4, which has a cam slot 233 formed near the free end thereof. Projecting into the camming portion of the slot 233 is a roller 234 which extends from a plate 235 having its lower end forked so as to straddle the shaft 6. Upon the beginning of the movement of the shaft 6 the cam slot 233 will elevate the plate 235 through its pin 234, so that the upper end of said plate 235 will pass in the rear of a stud 236, which projects through a slot 237 formed in the right hand side frame 3. This lug 236 projects from the vertical arm 238 of a bell crank lever and is straddled by a portion of the total key 199. A pin 239 projecting from the side frame 3 engages with the rear edge of the plate 235, so as to prevent rotary movement of the plate 235 about the shaft 6 in a clockwise direction. This plate is held in engagement with the pin 239 by a spring 240, the ends of which are fastened to the plate 235 and the side frame 3. From this it will be seen that when either one of the amount keys 1 or the "No Sale" key 137 is operated, the plate 235 will be elevated and pass to the rear of the stud 236 and thereby lock the total key 199 from operation. When the total key 199 is operated first, the bell crank carrying the stud 236 will be rotated in a clockwise direction about the shaft 202 and the horizontal arm 241 of the previously mentioned bell crank, which carries the stud 236, will pass in front of an arm 242 extending upwardly from the shaft 9 and remain in front of said arm 242 until the total key 199 is restored to normal position, as previously described. As the shaft 9 carrying the arm 242 is rocked when either one of the amount keys 1 or the "No Sale" key 137 is operated, it will be seen that it is impossible to rock said shaft when the total key is depressed, and consequently the keys 1 and 137 are prevented from being operated. When the total key is depressed and the total elements 44 are reset to zero, the differentially movable frames 5 will be elevated, as previously described, and consequently the shaft 6 will be rocked. This rocking of the shaft 6 will elevate the plate 235 by the cam slot 233 operating upon the roller 234 carried by the plate 235. This plate 235 in its upward movement, when the total key 199 is depressed, will pass in front of the stud 236 and when the total key 199 and the bell crank carrying the stud 236 is returned to normal position upon the beginning of the rotation of the shaft 21, as previously described, the stud will contact with the rear edge of the plate 235 and carry the upper end of said plate forwardly about the shaft 6 against the tension of the spring 240, after which the said plate 235 will be

cammed downwardly out of contact with the stud 236 upon the return of the shaft 6 by the plate 232 carried by said shaft, after which the plate 235 will be returned to its normal position in contact with the stud 239 by the spring 240. 70

The shaft 50, see Fig. 2, has a rearwardly and downwardly extending arm 243 which carries a flip pawl 244. This flip pawl is arranged to engage and depress the forward end of a centrally pivoted lever 245 as the shaft 50 is returned toward normal position, and thereby elevate a drawer plunger 246 which is secured to the rear end of the lever 245. The lower end of this plunger is arranged to engage and hold a cash drawer, not shown, in an inaccessible position when said plunger is in its normal position, and when the said plunger is elevated the drawer is arranged to be propelled forwardly by 80 any suitable form of spring as is well understood in the art. 85

While the form of mechanism herein shown and described is admirably adapted to fulfil the objects primarily stated it is to 90 be understood that it is not intended to confine the invention to the one form of embodiment herein shown and described as it is susceptible of embodiment in various forms all coming within the scope of the 95 claims which follow.

What is claimed is:

1. In an accounting machine, the combination with a plurality of totalizer elements, of actuators therefor normally in engagement therewith, manipulative devices arranged in groups, a frame for each group of manipulative devices and differentially operated thereby, devices connecting the actuators and frames, and an operating mechanism constructed to disengage the actuators from the totalizer elements and having connections for positively returning the actuators to normal positions. 101

2. In an accounting machine, the combination with a plurality of totalizer elements, of differentially movable devices, and keys for operating said devices, actuators for the totalizer elements movably mounted upon the differentially movable devices and normally in co-operative relation with the totalizer elements, and an operating mechanism constructed to disestablish the co-operative relation between the actuators and the totalizer elements, and having connections for 111 positively returning the actuators to normal 121 positions.

3. In an accounting machine, the combination with a plurality of totalizer elements, of differentially movable devices and keys 121 for operating said devices, actuators for the totalizer elements movably mounted upon the differentially movable devices and normally in engagement with said elements, a frame for guiding the actuators, an operat- 131

ing mechanism for rocking the guiding frame and thereby carrying the actuators out of engagement with the totalizer elements, and means actuated by the operating 5 mechanism for positively returning the differentially movable devices and the actuators carried thereby to normal positions.

4. In an accounting machine, the combination with a plurality of totalizer elements, 10 of differentially movable devices and keys for operating said devices, latches for holding the movable devices in operated positions, actuators for the totalizer elements movably mounted on the differentially movable devices and normally in engagement 15 with said elements, a frame guiding the actuators, an operating mechanism constructed to rock the frame and thereby to carry the actuators out of engagement with the totalizer elements, and means, actuated by the operating mechanism, for releasing the latches and for positively returning the differentially movable devices and the actuators carried thereby to normal positions.

25 5. In an accounting machine, the combination with a plurality of totalizer elements, of actuators therefor normally in engagement therewith, slides carrying said actuators, differentially movable frames connected to the slides, and keys operating said frames and constructed to prevent excess movement of said frames.

30 6. In an accounting machine, the combination with a plurality of totalizer elements, of actuators therefor normally in engagement therewith, differentially movable frames connected to the actuators, keys operating said frames and constructed to prevent excess movement of the frames, and an 35 operating mechanism constructed to disengage the actuators from the totalizer elements and having connections for positively returning the actuators and the differentially movable frames to normal positions.

45 7. In an accounting machine, the combination with a plurality of totalizer elements, of actuators therefor normally in engagement therewith, differentially movable frames connected to the actuators, keys operating said frames and constructed to prevent excess movement of the frames, devices 50 for latching the frames in adjusted positions, and an operating mechanism constructed to release the latching devices and 55 to disengage the actuators from the totalizer elements and having connections for returning the actuators and the differentially movable frames to normal position.

8. In an accounting machine, the combination with a differentially movable element, of a series of keys for operating the same, an indicator, an actuator for said indicator, a plate having a triangular aperture and connecting the differentially movable element and the indicator actuator, a

rod movable in said aperture and means for operating said rod, whereby it will engage with one of the walls of the aperture and move the indicator, through its actuator, a distance determined by the position 70 of the differentially movable element.

9. In an accounting machine, the combination with a differentially movable element, of a series of keys operating the same, an indicator, an actuator for said indicator, a plate having a triangular aperture approximately at its center and connected at its forward end to the differentially movable element and at its rearward end to the indicator actuator, a rod movable in the 75 aperture in the plate, and means for moving the rod so as to contact with one of the walls of the aperture, thereby moving the rearward end of the plate and the indicator, through its actuator, after the differentially movable element has been operated by the keys.

10. In an accounting machine, the combination with a differentially movable element, of a series of keys operating the same, 90 means for latching said element in its operated position, an indicator, an actuator for said indicator, a plate having a triangular aperture approximately at its center and connected at its forward end to the differentially movable element and at its rearward end to the indicator actuator, a rod movable in the slot of the plate, means for moving the rod so as to contact with one of the walls of the slot thereby moving the rearward end 95 of the plate and the indicator, through its actuator, after the differentially movable element has been operated by the keys, and means for retaining the indicator in its adjusted position.

11. In an accounting machine, the combination with type carriers for recording upon a record strip items and the totals thereof, of a plurality of totalizer elements, manipulative devices controlling the type carriers 110 in the recording of items, means, also controlled by the manipulative devices, for actuating the totalizer elements, mechanism for resetting the said elements to zero, a lock 115 for the resetting mechanism, a total key having connections to release said lock, and means operated by the total key for placing the type carriers under the control of the totalizer elements so that when said elements are reset the type carriers will be 120 moved proportionate distances in order to print the total.

12. In an accounting machine, the combination with type carriers for recording upon a record strip items and the totals thereof, of a plurality of totalizer elements, 125 differentially movable devices constantly connected to the type carriers, keys for operating the differentially movable devices, actuators for the totalizer elements carried by 130

the movable devices and normally in engagement with said elements, means for resetting the totalizer elements in a reverse direction from that in which they are moved by the 5 actuators, a total key, and means, controlled by said total key, for engaging the actuators with the totalizer elements in such a manner so that when the totalizer elements are moved by the resetting means they will, through the actuators and the differentially movable devices, set the type carriers in 10 positions to print the total.

13. In an accounting machine, the combination with type carriers for recording 15 upon a record strip items and the totals thereof, of a plurality of totalizer elements, differentially movable actuators for the totalizer elements, manipulative devices controlling the movements of the actuators, 20 means for resetting the totalizer elements, a total key, and means, controlled by said total key, for shifting the actuators so that upon the resetting of the totalizer elements the actuators will control the positioning of the 25 type carriers for printing the total.

14. In an accounting machine, the combination with type carriers for recording upon a record strip items and the totals thereof, of a plurality of totalizer elements, 30 actuators for said elements, manipulative devices controlling the recording of items upon the record strip and the entering thereof by the actuators upon the totalizer elements, normally inoperative means for resetting the 35 totalizer elements to zero positions, and mechanism for rendering the resetting means operative and for shifting the actuators so that when said totalizer elements are reset the actuators will control the positioning of the type carriers for printing the 40 total.

15. In an accounting machine, the combination with type carriers for recording upon a record strip items and the totals 45 thereof, of a plurality of totalizer elements, differentially movable devices constantly connected to the type carriers, double faced rack plates carried by the movable devices, for actuating the totalizer elements, one face 50 of each rack plate being normally in engagement with said elements, manipulative devices for controlling the movement of the differentially movable devices, normally inoperative means for resetting the totalizer 55 elements to zero positions, and mechanism for rendering the resetting means operative, and for shifting the rack plates to positions wherein the other faces of said plates will engage with the totalizer elements, in order 60 that when said elements are reset to zero they will, through the rack plates and the differentially movable devices, position the type carriers for printing the total.

16. In an accounting machine, the combination with type carriers for recording 65

upon a record strip items and the totals thereof, of a plurality of totalizer elements, operating keys having connections for positioning the type carriers to record items, and for actuating the totalizer elements, normally inoperative means for resetting the totalizer elements, mechanism for rendering the resetting means operative and placing the type carriers under the control of the totalizer elements so that when the said elements are reset the type carriers will be positioned for printing the total, a platen for taking an impression from the type carriers and a lever for operating said platen. 70 75

17. In an accounting machine, the combination with type carriers for recording upon a record strip items and the totals thereof, of a plurality of totalizer elements, differentially movable devices constantly connected to the type carriers, actuating 80 racks for the totalizer elements carried by the movable devices, keys actuating the differentially movable devices, resetting means for the totalizer elements, means for normally locking said resetting means, a total 85 key, mechanism operated by said total key for unlocking the resetting means and connecting the actuating racks and the totalizer elements in such a manner so that when the totalizer elements are reset the type carriers, 90 through the actuating racks and the differentially movable devices, will be positioned for printing the total, a platen for taking an impression from the type carriers, and a 95 lever for operating said platen. 100

18. In an accounting machine, the combination with type carriers for recording upon a record strip items and the totals thereof, of totalizer elements, manipulative devices controlling the recording of items and the 105 entering thereof upon the totalizer elements, resetting means for the totalizer elements, mechanism, connected to the totalizer elements, during the resetting operation, for positioning the type carriers to print totals, 110 a bicolor inking ribbon through which the items and total are recorded upon the record strip, and means actuated by the resetting means for shifting the inking ribbon so as to record the total in a color different 115 from that of the items.

19. In an accounting machine, the combination with type carriers for recording upon a record strip items and the totals thereof, of totalizer elements, manipulative devices 120 controlling the recording of items and the entering thereof upon the totalizer elements, resetting means for the totalizer elements, mechanism, connected to the totalizer elements during the resetting operation, for positioning the type carriers to print totals, a 125 platen for taking an impression from the type carriers, a lever operating the platen, a bicolor ribbon through which the items and total are recorded upon the record strip, 130 135

and means, actuated by the resetting means, for shifting the inking ribbon so as to record totals in a color different from that of the items.

- 5 20. In a machine of the class described, the combination with a differentially movable member, of a series of keys for operating same and constructed to be coupled thereto, means for latching the differentially 70
10 movable member in its operated position, connections, controlled by the keys, and constructed to hold said latching means out of latching position until the end of the operative movements of the keys, an operating 75
15 lever, and means controlled by said lever for releasing the latching means and restoring the differentially movable member to normal position.

21. In an accounting machine, the combination with means for recording items and the totals thereof, of a totalizer, actuators having two rack portions, one for entering items upon the totalizer and the other for controlling the recording of totals, transfer 80
20 devices for the totalizer normally out of engagement therewith, a total key having connections for shifting the actuators so as to disengage one rack portion of each of the actuators from the totalizer and to engage 85
25 the other portions therewith, and means, controlled by said total key, for engaging the transfer devices with the totalizer while the actuators are being shifted.

22. In an accounting machine, the combination with a totalizer element, of an actuator therefor having two rack portions, one for entering items on said element and positioned normally in operated relation therewith, the other for controlling the recording 90
30 of totals from said element, and positioned normally out of operative relation with said element, transfer devices for said totalizer element normally out of operative relation therewith, a total key, means controlled by 95
40 said total key for shifting the actuator and thereby disestablishing the said operative relation of said one rack portion and establishing an operative relation between said other rack portion and said totalizer element, and means, controlled by said total 100
45 key, for connecting said transfer device to said totalizer element during said shifting of said actuator.

23. In a machine of the class described, the combination with a differentially movable member, of a series of keys for operating same and constructed to be coupled thereto, means for latching the differentially 105
55 movable member in its operated position, a frame, actuated by the keys, and constructed to hold the latching means out of operative position until the end of the operative movement of the keys, an operating lever, a lock for said lever released by the operation of 110
60 any of the keys, and means, controlled by 115
65

the operating lever, for releasing the latching means and for restoring the differentially movable member to normal position.

24. In a machine of the class described, the combination with a series of amount indicators, of amount keys for controlling said indicators, a special indicator constructed temporarily to conceal the amount indicators at each operation of the machine, an auxiliary indicator, a special key, and means, controlled by said special key, for causing the exposure of said auxiliary indicator and thereby the concealing of the amount indicators. 75

25. In a machine of the class described, the combination with a series of amount indicators and means for adjusting same, of a flash, means for moving the flash and concealing the indicators during the adjustment of said indicators and thereafter moving the flash and exposing the indicators, a special indicator normally in non-indicating position, and means for connecting the flash and the special indicator, so that when the flash is moved from concealing position the special indicator will be brought into indicating position. 80
85
90

26. In a machine of the class described, the combination with a series of amount indicators and means for adjusting same, of a flash, means for moving it and concealing the indicators thereby and then returning it to normal exhibiting position during each operation of the machine, a special indicator constructed to conceal the amount 100
95
105
110
115
120
125
130

indicators when it is operated, a special key, and a spring operated pawl controlled by said special key and constructed to connect the flash with the special indicator so that when the flash is returned to normal position the special indicator will be exposed. 110
115
120
125
130

27. In a machine of the class described, the combination with a series of amount indicators, of amount keys having connections to determine the movement of the indicators, an operating mechanism constructed to adjust the indicators an extent determined by the amount keys, a flash actuated by the operating mechanism at each operation of the machine, for concealing the indicators and then exposing the same, a special indicator, a special key, and means, controlled by the latter, for connecting the special indicator with the flash so that when the flash is given its exposing movement by the operating mechanism it will carry the special indicator to a position to display the characters thereon.

28. In an accounting machine, the combination with a plurality of indicators positioned to be viewed from different directions, mechanism connecting all said indicators and including elements connected to be moved in opposite directions and constructed to counter balance each other, and 130

means for driving said connecting mechanism by actuating one of said connected elements.

29. In an accounting machine, the combination with two indicators positioned to display various characters in opposite directions, of actuating racks for each indicator constructed to counter balance each other, devices permanently connecting said racks, 10 and including a shaft and gearing constructed to compel said racks to move in opposite directions, and driving devices connected to one of said actuating racks.

30. In an accounting machine, the combination with a plurality of totalizer elements, of actuators therefor normally in engagement therewith, slides carrying said actuators and pivoted thereto, differentially movable frames connected to the slides, and 20 separably operable keys for actuating said frames and constructed to prevent excess movement of said frames.

31. In an accounting machine, the combination with a plurality of totalizer elements, of actuators therefor normally in engagement therewith, slides carrying said actuators, pivoted frames capable of differential movement and connected to the slides, and keys operating said frames and constructed to prevent excess movement of said frames.

32. In an accounting machine, the combination with a plurality of totalizer elements, of actuators therefor normally in engagement therewith, differentially movable frames connected to the actuators, keys operating said frames, devices for latching the frames in adjusted positions, and an operating mechanism constructed to release 40 the latching devices and to disengage the actuators from the totalizer elements and having connections for returning the actuators and the differentially movable frames to normal position.

45 33. In an accounting machine, the combination with a plurality of totalizer elements, of actuators therefor normally in engagement therewith, differentially movable frames connected to the actuators, keys 50 operating said frames, devices for latching the frames and the keys in adjusted positions, and operating mechanism constructed to release the latching devices and to disengage the actuators from the totalizer elements and having connections for returning the actuators and the differentially movable frames to normal position.

34. In an accounting machine, the combination with type carriers for recording 60 upon a record strip items and the totals thereof, of a plurality of totalizer elements, manipulative devices controlling the type carriers in the recording of items, means also controlled by the manipulative devices, 65 for actuating the totalizer elements, mecha-

nism independent of said actuating means for the totalizer for resetting the totalizer elements to zero, a lock for the resetting mechanism, a total key having connections to release said lock, and means operated by the total key for placing the type carriers under the control of the totalizer elements so that when said elements are reset the type carriers will be moved proportionate distances in order to print the total. 70

35. In an accounting machine, the combination with type carriers for recording upon the record strip items and the totals thereof, of a plurality of totalizer elements, differentially movable devices constantly 80 connected to the type carriers, keys for operating the differentially movable devices and normally in engagement with said elements, means for resetting the totalizer elements in a reverse direction from that in 85 which they are moved by the actuators, and means for engaging the actuators with the totalizer elements in such a manner so that when the totalizer elements are moved by the resetting means they will through the 90 actuators and the differentially movable devices set the type carriers in positions to print the total.

36. In an accounting machine, the combination with type carriers for recording 95 upon a record strip items and the totals thereof, of a plurality of totalizer elements, actuators for said elements, manipulative devices controlling the recording of items upon the record strip and the entering 100 thereof by the actuators upon the totalizer elements, manipulative means for resetting the totalizer elements to zero positions, and mechanism for engaging the actuators with the totalizer elements so that when said elements are reset the actuators will control 105 the positioning of the type carriers for printing the total.

37. In an accounting machine, the combination with type carriers for recording upon 110 a record strip items and the totals thereof, of a plurality of totalizer elements, actuators for said elements, manipulative means controlling the recording of items upon the record strip and the entering thereof by 115 the actuators upon the totalizer elements, normally inoperative manipulative means independent of said actuators for resetting the totalizer elements to zero position, and a total key for rendering the resetting means 120 operative and for shifting the actuators so that when said totalizer elements are reset the actuators will control the positioning of the type carriers for printing the total. 125

38. In an accounting machine, the combination with type carriers for recording upon a record strip items and the totals thereof, of a plurality of totalizer elements, manipulative devices, actuators for the totalizer elements and the type carriers and operated 130

by the manipulative devices, manipulative means independent of said actuators for moving said totalizer elements in the reverse direction from that in which they are moved by the actuators, and another manipulative device for engaging the actuators with the totalizer elements so that the actuators will be operated by the totalizer elements when the latter are reset to move the type carriers proportionate distances in order to print the total.

39. In an accounting machine, the combination with type carriers for recording upon a record strip items and the totals thereof, of a plurality of totalizer elements, actuators for said elements, manipulative devices controlling the recording of items upon the record strip and the entering thereof by the actuators upon the totalizer elements, a manually rotatable shaft supporting said totalizer elements constructed, when turned, to reset the totalizer elements to zero position, and manipulative means for engaging the actuators with the totalizer elements in such a manner so that when the totalizer elements are moved by the resetting means they will through the actuators set the type carriers in positions to print the total.

40. In an accounting machine, the combination with a differentially movable member, of keys for positively operating said member, pivotally mounted pawls for latching said keys in operated positions, a spring pressed pawl for retaining said first pawl in latching position to latch said movable member in its adjusted position, and operating means for rendering said pawls ineffective for latching purposes and for positively restoring said actuators and keys to normal position.

41. In an accounting machine, the combination with a differentially movable member and a series of keys for operating the same, of means for latching the differentially movable member in its operated position, connections controlled by the keys and constructed to hold said latching means out of latching position until the end of the operative movements of the keys, and operating means for releasing the latching means and positively restoring the differentially movable member to normal position.

42. In an accounting machine, the combination with means for recording items and the totals thereof, of a totalizer, actuators having two rack portions one for entering items upon the totalizer and the other for controlling the recording of totals, transfer devices for the totalizer normally out of engagement therewith, a total key having connections for shifting the actuators so as to disengage one rack portion of each of the actuators from the totalizer and to engage the other portions therewith, means controlled by the total key for engaging the

transfer devices with the totalizer while the actuators are being shifted, and operating means for disengaging said actuators from said totalizers and restoring the actuators to normal position and constructed to cause said transfer devices to engage with the totalizer after the totalizer elements are reset and while the actuators are being restored to normal position.

43. In an accounting machine, the combination with a totalizer, of actuators normally in engagement with the totalizer, keys for operating said actuators, transfer devices for the totalizer normally out of engagement therewith, and operating means for positively restoring said actuators to normal position and constructed to engage said transfer devices with said totalizer while the actuators are being restored to normal position to prevent operation of said totalizer during such restoration.

44. In an accounting machine, the combination with indicators positioned to display various characters in opposite directions, a shaft, two pinions fast upon said shaft, an actuating rack constantly meshing with one of said pinions and with one of said indicators, a driving device connected to said rack, a second shaft, a third pinion supported by said second shaft and constantly meshing with the other pinion fast upon the first shaft, and an actuating rack constantly meshing with the other indicator and the third pinion and constructed to counterbalance said first rack.

45. In an accounting machine, the combination with a plurality of totalizer elements, of actuators therefor normally in engagement therewith, manipulative devices arranged in groups, a frame for each group of manipulative devices, and differentially operated thereby, devices connecting the actuators and frames, and an operating mechanism constructed to move the actuators to disengage them from the totalizer elements, and having connections for positively returning the actuators to normal positions.

46. In an accounting machine, the combination with a plurality of totalizer elements, of actuators therefor normally in engagement therewith, slides carrying said actuators, differentially movable frames connected to the slides, and keys operating said frames, normally disengaged therefrom and constructed to become connected to said frames upon operation of the keys, and to prevent excess movement of the frames.

47. In an accounting machine, the combination with a plurality of totalizer elements, of actuators therefor normally in engagement therewith, differentially movable frames connected to the actuators, keys operating said frames and constructed to prevent excess movement of the frames, and an operating mechanism constructed to move

the actuators to disengage them from the totalizer elements, and having connections for positively returning the actuators and the differentially movable frames to normal 5 positions.

48. In an accounting machine, the combination with a plurality of totalizer elements, of actuators therefor normally in engagement therewith, differentially movable 10 frames connected to the actuators, keys operating said frames, and constructed to prevent excess movement of the frames, and an operating mechanism constructed to disengage the actuators from the totalizer elements, and having connections for positively 15 returning the differentially movable frames and the operated keys to normal positions.

49. In an accounting machine, the combination with type carriers for recording upon 20 a record strip items and the totals thereof, of a plurality of totalizer elements, differentially movable actuators for the totalizer elements, manipulative means controlling the movement of the actuators, means for 25 resetting the totalizer elements, a total key, and means controlled by the total key for establishing a coöperative relationship between the actuators and the totalizers, so that upon resetting of the totalizer elements 30 the actuators will control the type carriers for printing the total.

50. In an accounting machine, the combination with type carriers for recording upon 35 a record strip items and the totals thereof, of totalizer elements, manipulative devices controlling the recording of items in the entering thereof upon the totalizer elements, reset-

ting means for the totalizer elements, mechanism connected to the totalizer elements during the resetting operation for positioning the type carriers to print totals, a total key for connecting said mechanism to the totalizer elements, a multi-color inking ribbon through which the items and totals are recorded upon the record strip, and means 40 actuated by the resetting means for shifting the inking ribbon so as to record the totals in a color different from that of the items.

51. In an accounting machine, the combination with type carriers for recording upon 50 a record strip items and the totals thereof, of totalizer elements, manipulative devices controlling the recording of items and the entering thereof on the totalizer elements, resetting means for the totalizer elements, 55 mechanism connected to the totalizer elements during the resetting operation for positioning the type carriers to print totals, a total key for connecting said mechanism to the totalizer elements, a platen for taking 60 an impression from the type carriers, a lever operating the platen, a multi-colored ribbon through which the items and totals are recorded upon a record strip, and means actuated by the resetting means for shifting the inking ribbon so as to record the totals in a 65 color different from that of the items.

In testimony whereof I affix my signature in the presence of two witnesses.

THOMAS CARROLL.
